VENDING MACHINE AND CONTROL
MECHANISM THEREFOR

Frank K. Maitland, Chicago, Ill.

Application June 8, 1936, Serial No. 84,090

2 Claims. (Cl. 194—1)

This invention relates to vending machines, and control mechanisms therefor, and has for a particular object the provision of a novel selective mechanism adapted to select a token or coin after a predetermined number of operations of the vending machine with which it is associated, and separate such token or coin from those previously deposited, and direct such selected coin into a receptacle separate from that which receives the bulk or majority of the coins or tokens deposited in the machine.

More particularly stated, an object of the invention is to provide a mechanism adapted for use with conventional types of coin control device for use with vending machines, whereby the coins or tokens deposited in the machine may be selectively directed into separate receptacles in a predetermined ratio, corresponding or representing respectively the net income for the "proprietor" of the vending machine, and the commission or participating profit for the "operator" thereof.

An additional object of the invention lies in the provision with such a selective mechanism of a tally or counter device for visually indicating either the proprietary or participating income of the vending machine.

Other objects and novel provisions of the invention will appear in view of the following detailed description, taken together with the appended drawing in which:

Fig. 1 is a fragmentary perspective view of a vending machine to which the invention has been applied;

Fig. 2 is a side elevation of my novel coin control taken along the lines 2—2 of Fig. 1;

Fig. 3 is a top plan view of the control mechanism shown in Fig. 2, and is taken along the lines 3—3 thereof;

Fig. 4 is a fragmentary vertical section taken along the lines 4—4 of Fig. 3 and includes sections of the coin receptacles and housing structure of the device shown in Fig. 1;

Fig. 5 is a bottom plan detail of the coin control shown in Fig. 2 and is taken along the lines 5—5 of the latter, while

Fig. 6 is a detail of the counter or tally mechanism taken along the lines 6—6 of Fig. 4, and includes circuit connections therefor.

My invention is particularly adapted to be incorporated with conventional types of coin control mechanism such as generally indicated at 10 in the figures of the drawing, and such as is particularly described in detail in U. S. Letters Patent No. 2,026,921, granted to W. A. Tratsch

and B. Grunig, dated January 7, 1936, or to other similar types of coin slide or control device well known in the art.

Such coin controls 10 usually include a frame member 12 (see Figs. 1 and 2 particularly) in which is slidably seated a coin slide 14 having a coin-receiving aperture 16 in which a coin is deposited by the user preliminary to reciprocating the slide 14 in the frame 12 for the operation of the vending or other device. Carried below the slide 14 in frame 12 is a second coin slide 18 having a coin discharge aperture 20 (Fig. 5) into which a coin originally deposited in aperture 16 is ultimately deposited after the slide 14 is urged inwardly, and the coin is thereafter discharged from the control member 10 into a suitable receptacle such as that marked "operator" in Fig. 4.

The detailed structure and operation of the coin control mechanism shown in the drawing herewith is not discussed except insofar as may be necessary for a proper illustration of the present invention, reference being had otherwise to the above-mentioned patent.

In Fig. 5, my improved selector mechanism is shown to comprise a ratchet wheel 24 mounted for rotation on the under side of the slide frame 12 by means of a screw pin 26, and mounted on frame 12 to one side of the ratchet wheel 24 is a locking pawl 28 normally spring-urged into engagement with ratchet 24 to prevent movement in one direction (counterclockwise in Fig. 5).

Pivotedly mounted on the underside of the coin slide 14 and adjacent the upper rear end of the latter, as shown in Fig. 5, is an elongated pawl 30 having an offset end portion with a depending tooth or pawl member 32, and a spring 34 adapted normally to urge the pawl 32 in a direction substantially lateral to or toward the slide 14. Thus, when the slide 14 is moved inwardly by the operator, the pawl tooth 32 will be advanced into engagement with one of the teeth of the ratchet wheel 24 and rotate the latter through a part of one revolution. Upon the return of the slide, the pawl 32, being suitably pitched relative to the pitch of the teeth of the ratchet wheel 24, will slip over the latter into normal position for another operation of the coin control, the locking pawl 28 being operative to prevent any movement of the ratchet wheel during the return stroke of the slide 14 and the pawl 30 carried thereby.

The ratchet wheel 24, as shown in Fig. 4, has a collar portion 36 from which is extended a switch finger 38 having an end cam portion 40 extended in a direction parallel to the axis of the ratchet wheel such that the cam portion de-

scribes a circular path eccentric of the path of the ratchet wheel when the latter is rotated by actuation of the slide 14.

Suitably positioned relative to the coin slide frame 12 and attached to the wall 11 of the vending device, is a switch member 42 of the usual jack or spring type which includes a pair of superposed elongated contact springs 43 and 44 having the contact spring 43 extended beyond the companion spring 44 to lie in the path of the cam portion 40 of the switch finger 38 in such manner that the rotation of the latter periodically engages the extended portion of the spring 43 to engage the contact of the latter with the contact of spring 44 and thereby close the switch.

Carried by the ratchet wheel 24 on the lower collar portion 36 of the latter, is a coin deflector plate 46 in the form of a rectangular plate extended in a plane substantially parallel to that of the slide and frame members of the coin control 10, except that the outermost end portion of the plate 46 opposite the collar 36 is sloped downwardly so as to provide a descending surface for coins deposited thereon. As a ratchet wheel 24 is rotated by the actuation of the slide member 14, the deflector plate 46 is similarly rotated and is so dimensioned and positioned relative to the discharge aperture 20 in the coin control mechanism as to be periodically positioned therebelow once during each cycle of revolution of the ratchet wheel 36. The positioning of the contact finger 38 and the deflector plate 46 on collar 36 of the ratchet wheel 24 is such that when the plate 46 is approaching the position below the aperture 20 (full line Fig. 5) from the dotted line position (Fig. 5), the cam portion 40 of finger 38 will be approaching the contact spring 43 and will engage the latter to close a circuit through the switch 42 upon completion of the movement of the ratchet wheel 24 and the deflector 46 from dotted line position to full line position (Fig. 5).

Positioned within the vending machine housing and to the left of the side wall 9 thereof (Fig. 4), is a coin discharge chute 48 having its opening registered with the discharge opening 20 in the coin control mechanism when the latter is in full stroke position, and adapted to receive the coins normally discharged from such mechanism with each operation of the latter by the user. However, as shown in Fig. 4, once during each cycle of revolution of the ratchet wheel 24 the deflector plate 46 will be positioned beneath the coin discharge aperture 20 so that a coin discharged therefrom, as shown in dotted lines in Fig. 4, will be deflected from the coin chute 48 into a second receptacle chute 50, indicated in the latter figure as "proprietor".

Mounted upon the side wall 9 of the vending machine housing is a tally or counter mechanism generally indicated at 52, and comprising a usual form of counter mechanism 54 and an electro-magnet 56 having an armature and lever arm assembly 58 operatively connected to the actuating shaft of the counter 54. The winding of the electro-magnet 56 is connected in circuit with the switch 42 and a source of supply 65 as shown in Fig. 6, and is adapted to be operated once for each closure of the latter switch by the switch finger 38 and the pawl and ratchet mechanism associated with the slide 14, as above described.

The tally or counter 54 may be of the visually

indicating type, and is positioned before a sight opening 60 in the side wall 9 of the housing.

Within the housing are two coin receptacles marked "operator" and "proprietor" and placed respectively to receive coins from the coin chutes 48 and 50. The "proprietor's" receptacle is accessible by means of a locked door 62 in the side wall 9 of the housing below the sight opening 60, and the "operator's" coin receptacle is accessible from the front wall 11 of the housing 10 and through a similar locked door 64.

Operation

In the use of the device, a proper coin may be inserted in the coin receiving aperture 16 in the slide 12, shown in Fig. 1, whereupon the user may push the slide 14 inwardly and release the vending mechanism in the usual manner, the deposited coin being retained within the coin slide momentarily when the latter is reciprocated to its normal position for the reception of another coin and the deposited coin moved rearwardly (Fig. 3) toward the coin discharge opening 20, and assuming the deflector plate 46 to be in the position shown in dotted lines in Fig. 5, the coin so discharged will normally descend into the chute 48 and thence into the coin receptacle marked "operator" (Fig. 4).

However, assuming the deflector plate 46 to be in the full line position as shown in Fig. 5, the coin discharged from the aperture 20 will fall onto the said plate and the coin will descend by gravity into the chute 50 and into the "proprietor's" receptacle or bin, the angular disposition of the plate 46 being such that the coin will readily slide toward the chute 50.

Subsequent deposits of coins in the corresponding reciprocations of the slide 14 by the user of the vending machine, will step the deflector plate 46 from the full line position of Figs. 4 and 5 away from the discharge opening 20, and thus permit subsequently discharged coins to descend into the chute 48 and the "operator's" receptacle, until the deflector plate 46 is again stepped around into the position shown in Figs. 2, 4, 45 and 5.

It will be observed that once during each cycle of operation of the deflector plate 46 and ratchet 24, the depending contact finger 38 will engage the extended contact spring 43 to close the switch 50 generally indicated at 42, and thus close a circuit through the counter electro-magnet 56, as shown in Fig. 6, and move the counter to indicate one additional unit.

The novel coin control mechanism provided by the present invention is particularly adapted for application to coin controlled vending devices of all types using a coin control mechanism of similar or analogous construction to that shown in the drawing herewith for purposes of illustration. And a particular object of the invention is to provide means in such devices for depositing a predetermined number of coins from the total number of coins inserted in the vending device, into a separate bin or receptacle so that the commission of the "operator" of the machine for example, can be automatically separated from the gross income of the machine, and also the amount of such commission or participation may be visually indicated at all times for examination by either the "proprietor" or the "operator" of the machine; and to further facilitate the accounting between the "proprietor's" and the "operator's" participation in the gross income of the machine, the receptacles in which the respective

shares of such income, corresponding to the coins alternately deposited in the two receptacles shown in Fig. 4, are provided with separate and locked doors, as shown at 62 and 64 in Fig. 1, so that the "proprietor" or the "operator", provided with a proper key may at any time remove the contents of his respective coin bin or receptacle.

The ratio of the coins, respectively deposited in the "operator's" and "proprietor's" bins, may be determined by the number of ratchet teeth 23 provided on the ratchet wheel 24, and for this purpose the ratchet wheel has been attached by means of a screw pin 26 (Fig. 5) to facilitate the ready interchange of ratchet wheels, the ratchet wheels corresponding to a change in the frequency with which the deflector plate 46 will be positioned below aperture 20.

While I have described a preferred form of construction in particular detail, it will be apparent that modifications and variations may be made in the construction and disposition of parts shown herein for illustrative purposes without departing from the spirit of the invention, and it will also be apparent that my control mechanism is applicable to a wide variety of vending devices in general, and I do not wish to be restricted to any of the limitations recited herein except as may be hereinafter provided by the appended claims.

Having thus described my invention, what I claim as new and desire to protect by Letters Patent is:

1. A coin control mechanism for vending machines, comprising a frame member, a coin slide movable therein and having a coin-receiving aperture, coin discharge means operably associated with said slide to discharge coins deposited in the said receiving aperture therein for movement into a coin receptacle; a ratchet wheel mounted on said frame for rotation in a plane substantially parallel with and below said coin slide, pawl means on said slide for moving said ratchet wheel responsive to movement of said slide, a deflecting plate carried by and rotatable with said ratchet wheel to deflect movement of coins discharged by said discharge means away from a said coin receptacle. 15

2. A coin control mechanism including a frame and a coin slide reciprocable therein to eject a deposited coin for movement into a coin receptacle, and selector means including a ratchet wheel pivotally mounted on the underside of said frame, a pawl mechanism carried by said slide and operable to step said ratchet wheel once for each reciprocation of the slide, and a selector plate pivotally supported for movement with said ratchet wheel beneath said slide and inclined away from the latter such that upon rotation of said ratchet wheel by reciprocation of the slide, said selector plate will periodically be positioned beneath said slide to deflect the movement of coins ejected therefrom away from said coin receptacle. 30
